UNITED STATES PATENT OFFICE.

FRANKLIN A. REECE, OF CHESTNUT HILL, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-CUTTER.

1,372,630.

Specification of Letters Patent. Patented Mar. 22, 1921.

Application filed December 3, 1918. Serial No. 265,113.

To all whom it may concern:

Be it known that I, FRANKLIN A. REECE, a citizen of the United States, residing at Chestnut Hill, county of Middlesex, State 5 of Massachusetts, have invented an Improvement in Buttonhole-Cutters, of which the following description, in connection with the accompanying drawing, is a specification, like characters on the drawing representing like parts.

This invention relates to the buttonhole-cutting devices which are employed on buttonhole sewing machines for cutting the buttonhole in the cloth, and it has particular 15 reference to a cutter adapted to cut a buttonhole with an eye at one end thereof.

Heretofore, the cutters for cutting buttonholes with the eye at the end thereof have usually comprised two coöperating elements, 20 one of which is in the form of a cutting bed and the other of which is a cutting element having a blade portion to cut the slit of the buttonhole, and a die portion to die out the eye of the buttonhole, both the blade and 25 the cutting die portion performing the cutting operation against the cutting bed. Where this construction is employed it is important that the cutting edge of the cutting element should be exactly parallel to 30 the surface of the bed during the cutting of the buttonhole because if this condition does not exist, then when the cutter is operated to cut a buttonhole, one end of the cutting edge will strike the cutting bed before the 35 other end with the result that the fabric will be only partially cut through at the latter end, thus producing a ragged instead of a clean cut. Moreover, the cutting of a buttonhole by means of a cutter having the 40 above-described construction requires the application of considerable power, especially where the material in which the buttonhole is to be cut is of a thick or heavy nature.

It is the object of my present invention to 45 provide a novel buttonhole cutter for cutting a buttonhole having an eye at one end which will produce a clean cut at all times with less expenditure of power than is required in operating a buttonhole cutter of 50 the type above described.

I secure this end by so constructing the two elements of the cutter that the slit portion of the buttonhole will be cut with a shearing cut, while the eye portion will be

died out by means of a cutting die coöperating on a cutting bed. I also preferably use a construction in which the slit portion of the buttonhole will be cut before the eye portion thereof because by this means a less expenditure of power is required than if the entire buttonhole is cut at once.

In order to give an understanding of my invention, I have illustrated in the drawings a selected embodiment thereof which will now be described, after which the novel 65 features will be pointed out in the appended claims.

Figure 1 is a view of the cutting elements of a buttonhole cutting machine which embodies my invention;

Fig. 2 is a section on the line 2—2, Fig. 3;

Fig. 3 is a bottom side view of Fig. 2;

Fig. 4 is a section on substantially the line 4—4, Fig. 1;

Fig. 5 is a section on the line 5—5, Fig. 3;

Fig. 6 is a perspective view of the cutting element;

Fig. 7 is a perspective view of the bed element.

Fig. 8 is a view of a cut buttonhole.

80

In the drawings, 1 indicates a portion of the usual lever or arm on which the cutter is mounted, and 2 designates the bed element on which the work rests and which coöperates with the cutter to cut the buttonhole. 85 These parts may have any suitable construction, but are herein shown as of the same general type as illustrated in United States Patent No. 1,188,945, June 27, 1916.

My improved cutter comprises two cutting portions, one of which is adapted to cut the slit 3 of the buttonhole and the other of which is adapted to cut the eye 4 thereof. The slit-cutting portion of the buttonhole is in the form of a blade 5 which is secured to a suitable holder 6 that in turn is detachably secured to the end of the arm 1 by some suitable means, as by means of a set-screw 7. The eye-cutting portion of the cutter is in the form of a cutting die 8 which is preferably made as an integral part of the holder 6, said cutting die being formed with the circular cutting edge 9 having the shape of the eye 4 of the buttonhole. The holder is made with the vertical face 10 against which the slit-cutting blade 5 rests, said blade being detachably secured to the holder by means of suitable screws 11. The

90

105

cutting blade 5 will preferably be arranged so that its cutting edge 12 projects below the cutting edge 9 of the eye-cutting portion 8, and if desired, said cutting edge 12 may 5 have the V-shape shown, although this is not essential.

The bed member 2 is provided with a cutting bed 15 of some soft material, such, for instance, as brass with which the cutting die 10 8 coöperates to cut the eye portion 4 of the buttonhole, and it is also provided with the slit 13 which coöperates with the cutting blade 5 to cut the slit 3 of the buttonhole. The slit 13 has a width to freely receive the 15 cutting blade 5, and the edges 14 of the slit serve to support the fabric each side of the blade 5 as it descends.

Since the cutting edge 12 of the blade 5 extends below the cutting edge 9 of the die 20 portion 8, it will follow that as the arm 1 moves downwardly to cut the buttonhole, the edge 12 of the blade 5 will first engage the goods and cut the slit 3, after which the cutting edge 9 of the cutting die 8 will come 25 against the fabric and coöperate with the cutting bed 15 to die out the eye 4 of the buttonhole.

The slit and eye of the buttonhole are thus cut at separate times, and as a result a less 30 expenditure of power is required to cut the buttonhole than would be the case if the entire buttonhole were cut at once.

Since the cutting blade 5 operates to cut the slit portion 3 with a shearing cut it is 35 not necessary or essential that the cutting edge of the blade should always be maintained in parallelism with the edge 14 of the slit or the top of a bed member as is the case where the slit is cut by a knife which 40 coöperates with the bed. Furthermore, since the lateral or transverse dimension of the die portion 8 is relatively small compared to the length of the buttonhole a slight departure from a true parallel relation 45 between the cutting bed and the face of the cutting die, which would be sufficient to cause imperfect cutting at the end of the slit if the entire buttonhole were cut against the cutting bed, will not be sufficient to 50 cause any imperfection in merely dieing out the eye of the buttonhole. Hence with the construction herein shown, it is not so essential that the cutting bed and the cutting edge of the die should be in exact parallel 55 relation during the cutting operation as is the case where the entire buttonhole is cut by a knife operating against a cutting bed.

In sewing machines of the type herein illustrated the bed element 2 is mounted on a pivoted arm 36 which is operated at the 60 proper time to swing the bed into position to coöperate with the knife and because of this pivoted construction the cutting bed is apt to lose its correct parallel relation with the cutting edge of the die after the machine has 65 been in use. With my improvements this loss of alinement is of no moment because a clean cut can always be made.

In order to produce a clean cut at the junction of the eye 4 and slit 3 of the buttonhole, I propose to form the front side of the cutting die 8 with a slit 17 into which the rear edge of the blade 5 is entered, as clearly seen in Fig. 6. During the cutting of the buttonhole, therefore, the slit 3 which 75 is cut first will extend into the portion of the fabric which is died out in forming the eye thereby making a clean cut.

The holder 6 is provided with an opening 16 into which the died-out portions of the 80 fabric pass as the buttonholes are cut.

I claim:

1. In a buttonhole sewing machine, the combination with a supporting arm having a dove-tail slot in its end, of a cutting element sustained by said arm and comprising a holder having a dove-tail head to fit said slot and being cut away on one side to form a vertical face terminating on its upper end at a shoulder, and a cutting blade overlying 90 and secured to said face, the portion of said holder in the rear of said face being shaped to form a cutting die, and a coöoperating cutting element in the form of a bed element provided with a slit to receive and co- 95 operate with the blade to cut the slit of the buttonhole and a bed portion to coöperate with the die to die out the eye of the buttonhole.

2. A buttonhole cutter comprising two 100 cutting elements, one of which has a portion provided with a slit and a bed portion raised slightly above the slit, said slit extending into the edge of the bed portion, and the other of which has a hollow cutting die 105 portion that operates against the bed to die out the eye of the buttonhole, and a shearing blade which enters and coöperates with said slit to cut the slit of the button-hole, the rear end of said blade extending through 110 the wall of the cutting die.

In testimony whereof, I have signed my name to this specification.

FRANKLIN A. REECE.
